(57) **CLAIM**

The ornamental design for a refrigerator, as shown and described.

DESCRIPTION

FIG. 1 is a front perspective view of the refrigerator showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view showing the design in a state of use;

FIG. 9 is a perspective view showing the design in another state of use;

FIG. 10 is a front view of FIG. 9;

FIG. 11 is a back view of FIG. 9;

FIG. 12 is a left side view of FIG. 9;

FIG. 13 is a right side view of FIG. 9;

FIG. 14 is a top plan view of FIG. 9;

FIG. 15 is a bottom plan view of FIG. 9;

FIG. 16 is a perspective view showing the design in yet another state of use;

FIG. 17 is a front view of FIG. 16;

FIG. 18 is a back view of FIG. 16;

FIG. 19 is a left side view of FIG. 16;

FIG. 20 is a right side view of FIG. 16;

FIG. 21 is a top plan view of FIG. 16;

FIG. 22 is a bottom plan view of FIG. 16; and,

FIG. 23 is a perspective view showing the design in still another state of use.

(Continued)

The broken lines depict portions of the refrigerator that form no part of the claimed design. The dash-dot broken lines define the bounds of the claimed design and form no part thereof.
